CAB ROOF LAMP

Philip H. Stevens, Syracuse, and David O. Chase, Camillus, N.Y., assignors to R. E. Dietz Company, Syracuse, N.Y., a corporation of New York

Filed Nov. 26, 1965, Ser. No. 88,220

Term of patent 14 years

(Cl. D48—32)

FIGURE 1 is a side elevational view of a cab roof lamp embodying our new design, the other side being a mirror image of the side shown;

FIGURES 4 and 5 are end elevational views thereof as viewed from the left and right, respectively, in FIGURE 1.

We claim:

The ornamental design for a cab roof lamp, substantially as shown and described.
